UNITED STATES PATENT OFFICE.

EUGENE ATWOOD, OF STONINGTON, CONNECTICUT, ASSIGNOR TO THE ATWOOD-MORRISON COMPANY, OF SAME PLACE.

SELF-BALANCING SPINDLE.

SPECIFICATION forming part of Letters Patent No. 665,161, dated January 1, 1901.

Application filed January 6, 1900. Serial No. 541. (No model.)

To all whom it may concern:

Be it known that I, EUGENE ATWOOD, a citizen of the United States, and a resident of Stonington, in the county of New London and 5 State of Connecticut, have invented a new and useful Improvement in Self-Balancing Spindles, of which the following is a specification.

My invention relates to a self-balancing spindle in which the supporting-tube which 10 carries the spindle is supported on the floor of an oil-cup and the wear tending to throw the spindle out of its true original position is avoided by the constant supply of a thin film of oil between the bottom of the cup and the 15 bearing on the tube.

In the accompanying drawings, Figure 1 represents a spindle and its supporting-tube and one form of the tube-support in side elevation. Fig. 2 is a top plan view of the 20 same. Fig. 3 is a view of the spindle-supporting tube and parts immediately connected therewith in vertical section on the plane of the line 3 3 of Fig. 2, and Fig. 4 is a cross-section of another form of tube-support.

25 The spindle is denoted by A.

The whirl is denoted by B and is here shown as adapted for either a band or belt; but it is to be understood that the ordinary form of whirl for a band alone or for a belt 30 alone might be substituted for the whirl here shown, as this forms no part of my present invention.

The supporting-tube in which the spindle is mounted is denoted by C and is provided 35 intermediate of its ends with an annular inverted cup c, from the rim of which there extends a lateral flange c', which forms the supporting-tube bearing.

The tube-support consists of an annular 40 cup D, having a central opening d, through which the tube C extends, bringing the tube-bearing c' into position to rest upon the bottom of the annular cup D. The cup D may have an oil-feed spout d' opening to the exterior of the cup and connecting with the bottom of the cup for the purpose of feeding oil into the annular cup D to lubricate the bottom of the said cup and form a thin film of oil between the bearing c' of the tube and 45 the bottom of the cup. The tube-supporting cup D is here shown as connected by a neck 50

d² with a pintle E, by which the spindle and its support may be secured to a rail; but this particular means of securing the spindle to the rail is immaterial so far as my present 55 invention is concerned, and I wish it to be understood that it is not limited to such structure. Another form of support (illustrated in Fig. 4) shows the supporting-cup D' formed in the rail E' and a simple hook e 60 employed to prevent the spindle from jumping out of position.

The tube C, including the bolster and step-bearings, is drawn toward the bottom of the cup D and held in position by means of a 65 cup-nut F, having a screw-threaded engagement with the lower end of the tube and receiving within its cup portion one end of a spiral spring G, the opposite end of the spring bearing against the bottom of the cup D. 70 The spring G is compressed by screwing the nut F onto the lower end of the tube, and its tension therefore is exerted in a direction to yieldingly hold the tube-bearing c' on the bottom of the cup D against the lateral pressure of the band or belt which may be employed to drive the spindle. The tube C is conveniently held against a rotary movement with respect to the cup D by means of a lug or feather d³, projecting into the opening d 80 through the cup D and adapted to enter an elongated groove c² in the wall of the tube.

A guard-cap H has a screw-threaded engagement at h with the exterior of the inverted cup c on the tube and has an opening h' 85 in its top, which permits it to be slid over the top of the spindle and its whirl into position to be screwed onto the tube-bearing. A laterally-extending flange h² on the cup projects over the mouth of the support D. 90

The slight rocking movement imparted to the tube by the pressure of the band or belt in driving the spindle has a tendency to draw the oil in the cup D between the bearing c' and the bottom of the cup D, thereby keeping it constantly lubricated and preventing the wear which would tend to throw the spindle out of a true position.

What I claim is—

1. The combination with a spindle and a tube for supporting the spindle, the tube being provided with a downwardly-projected

annular bearing spaced from the body of the tube, of a tube-support provided with an annular bearing for receiving the said bearing on the tube, the said support-bearing having an annular wall adapted to extend upwardly into the space between the body of the tube and its bearing and an outer upwardly-extending wall, whereby an annular cup-bearing is formed for the reception of the bearing on the tube, substantially as set forth.

2. The combination with a tube-support free to swing bodily and provided with an annular cup-bearing provided with an inner annular wall, of a spindle-supporting tube

provided with an annular bearing projected 15 downwardly and spaced from its body to engage the bottom of the annular cup-bearing on the swinging support, substantially as set forth.

In testimony that I claim the foregoing as 20 my invention I have signed my name, in presence of two witnesses, this 26th day of December, 1899.

EUGENE ATWOOD.
